(57) **CLAIM**

The ornamental design for robotic exoskeleton suit for lifting loads as shown and described.

DESCRIPTION

1. Robotic exoskeleton suit for lifting loads

1.1 : Perspective

1.2 : Front

1.3 : Back

1.4 : Left

1.5:Right

1.6:Top

1.7: Bottom

Reproduction 1.1 is a perspective view of a robotic exoskeleton suit for lifting loads showing our new design; reproduction 1.2 is a front elevation view thereof; reproduction 1.3 is a rear elevation view thereof; reproduction 1.4 is a left

(Continued)

side elevation view thereof; reproduction 1.5 is a right side elevation view thereof; reproduction 1.6 is a top plan view thereof; reproduction 1.7 is a bottom plan view thereof.

The broken lines and the half-tone areas within the broken lines depict portions of the robotic exoskeleton suit for lifting loads that form no part of the claimed design.
